UNITED STATES PATENT OFFICE.

WILLIAM L. SILVEY, OF CINCINNATI, OHIO.

DYNAMO-ELECTRIC MACHINE.

SPECIFICATION forming part of Letters Patent No. 400,130, dated March 26, 1889.

Application filed November 17, 1887. Serial No. 255,376. (No model.)

To all whom it may concern:

Be it known that I, WILLIAM L. SILVEY, a citizen of the United States, residing at Cincinnati, in the county of Hamilton and State 5 of Ohio, have invented certain new and useful Improvements in Dynamo-Electric Machines, of which the following is a specification.

My invention relates to improvements in 10 dynamo-electric machines in which a circular field-magnet is used in connection with a circular armature, and in the means by which I am able to make the field-magnet cheaply and in a substantial manner, and a machine 15 designed to give almost double the output in ampères with almost the same number of volts that could be got out of the two-pole type of dynamo. In order to accomplish this result I have constructed a machine in which 20 I never have less than four poles, and may have as many as twelve or more. In every case I have the same number of poles on the armature as on the field-magnet, and of course, the coil between the poles on the armature 25 being of the undivided type, it is evident that I will have the same number of segments in my commutator as I have poles on my field-magnet and armature—*i. e.*, a machine having four poles on the field-magnet and armature will have four segments in the commutator, and so on. In this way I have a machine easy to build, and if it should need repair it can be done at little expense.

Machines of the Gramme type having many 35 segments in the commutator frequently get short circuits in the commutator between contiguous segments, in which case the coil which is short-circuited will create an abnormal current, and consequently heat the wire 40 and char the insulation, which of course will disable the armature, if not entirely destroy it; but an armature constructed on my plan, in case two segments in the armature get short-circuited, there being no other coils in 45 series with the coil to keep up the electro-motive force, it is evident that the armature at once ceases to make a current, and in this way all danger to the coil is removed. The reason of this is the fact that the resistance 50 of the short circuit is practically nothing, while the resistance of the field-magnet circuit, which

must be supplied in order to create any current in the armature, is considerable. Now, therefore, a current will divide between two circuits in proportion to their resistance. 55 Consequently the difference between the resistance of the field-magnet circuit and that of the short circuit is so great that nearly all of the current in the machine will flow through the circuit of low resistance, and consequently there will not be enough current 60 flow through the field-magnet to keep the machine charged, and as a result the machine will cease to make any current. This will continue until the short circuit is removed, at 65 which time the machine will make current as before. This short-circuiting and its result act as a safety device more perfect than any other means, and as a result I have never had a burned-out armature since I adopted this 70 manner of construction.

Referring to the accompanying drawings, which are made a part hereof, similar letters referring to similar parts, Figure 1 is a front elevation of the machine with the hanger-arm 75 B broken away on one end to show the manner of coring the pole-piece a. Fig. 2 is an end view diagram of the electric circuits. Fig. 3 is a perspective view of the armature, showing the manner of mounting the armature-blanks F, which constitute the armature-ring, on the bolts e with the triangular jam-nut, Fig. 4, for pressing the blanks tightly together; and Fig. 5 shows an armature-blank as stamped out, and of which the armature 80 is composed.

The field-magnet consists, essentially, of an iron ring, on which wedge-shaped pole-pieces are cast. This wedge-shaped pole-piece has its narrowest point projecting inward, in front 90 of which the ring-armature F revolves. This field-pole is made as narrow as possible, in order to carry the magnetism of the field-magnet, for I have found that a multipolar machine does not require the poles to expand as 95 much on their armature-face as a machine having only two poles.

In the construction of my field-magnet I cast the entire ring in one piece with a dry sand core in two or more of the poles, so as to 100 make a hole, a, which extends the entire length of the pole. After the casting has

been bored out and finished up ready for the wiring I drive wedges into the cored holes and split the casting into two or more parts. This allows the field-magnet to be then wound 5 on a machine, whereas if the ring were solid it would have to be wound with a shuttle, which is a very slow and difficult piece of work. By this simple means of coring the poles I am able to wind a field-magnet for less 10 than one-half what it would cost were it cast solid or inseparable. After the field-magnet has been split there are ragged edges where the iron was broken. These act as sutures to keep the parts from slipping on each other, 15 and they also make a more perfect joint magnetically than it would be possible to obtain were the faces planed. In fact, a broken joint is much more solid and better than a planed joint. This is one part of my invention on 20 which I put particular stress. The parts of the field-magnet are held together by the expanded ends of the hanger-arm B, one of which is bolted to each end of the field-magnets for the support of the shaft. The armature 25 is composed of laminated iron rings separated from each other by rings of paper of the same shape. On these rings, which are stamped out of sheet-iron, at regular intervals there is a wedge-shaped pole-piece, 30 the base of the wedge projecting outward, through the center of which a hole is stamped. Through these holes there pass rods to keep the armature-rings firmly secured together and act as carriers. These rods project at 35 each end and pass through the triangular jam-nut F', which serves the purpose of pressing the blanks of paper and iron together and keeping the brass end plates from coming in contact with the coils, and then through 40 corresponding hole in brass flange-plates Z, which are secured to the shaft, so that when the parts are all mounted together they constitute a drum of the most solid construction, and the depressions on the armature 45 being wound full of wire there are few or no projections to catch against currents of air, and therefore the loss of mechanical power from this cause is almost entirely overcome. The armature-coils are all wound 50 in one direction and joined together into a continuous circuit. At the junction between the coils there are joined leading-wires g g', which connect alternately to the different junctions, and the coils all being wound round 55 in one direction, while the poles on the field-magnet are of alternately north and south polarity, it is evident that the leading-wires will collect currents of opposite polarity. These junction-wires are joined to two shaft- 60 wires, h h', which pass out through the shaft and connect to the alternate segments of the commutator, from which the current escapes by the brushes d d' to the field-magnet and outside circuit.

65 It will be observed that the field-magnet is compound wound for the purpose of automatic regulation. For arc lighting the fine-

wire coils are so proportioned that the coarse wire is only required to create a sufficient electro-motive force to overcome the resistance of one arc. The fine wire, which is of high resistance, receives but little current, and consequently does but little work; but as the resistance of the external circuit increases more current is diverted into the fine-wire 75 coil, and consequently the armature generates a correspondingly high current until the limit of capacity is reached. This is my manner of regulation of arc-circuits.

For incandescent circuits, or where a constant potential is desired with a variable quantity of ampères, I wind my field-magnet in such proportion between the fine wire and coarse wire that the fine wire is only capable of generating an electro-motive force of, say, 85 one hundred volts and five ampères. This current escapes through the coarse-wire coils to the line. As more lamps are thrown into the main line in multiple-arc circuit, the resistance in that circuit is correspondingly reduced. As the resistance in this circuit decreases, more current flows through that circuit and less through the shunt or fine-wire coils on the field-magnet, and as a consequence the machine becomes practically self-regulating. 90 The current escapes from the commutator to brush d', where it divides into two circuits, before mentioned. The fine-wire circuit S flows to the field-magnet coils which are joined in the series, each alternate coil 100 being wound in a different direction. This makes the pole-pieces all consequent poles on the field-magnet. The current in the fine wire after traversing all the field-magnet coils returns by the fine wire T to brush d and 105 commutator E. The coarse-wire coil traverses the field-magnet in the same direction as the fine-wire coil. The current enters field-magnet at brush d' and terminal wire V, and after traversing all the field-coils L in a direction the same as the fine-wire coils, before 110 described, escapes by terminal wire to binding-post K, thence to line and lamps Q R, from whence it returns to binding-post P, and thence by leading-wire U to brush d, thus 115 completing its circuit.

By constructing a machine in the form embodied in my present invention I utilize both ends of my field-magnet core, and also the induction of one side of my field-magnet 120 coils on the armature. In this way I get the greatest electrical efficiency, and also a machine which is extremely light and easy to construct.

Having described my invention, what I 125 claim as new, and wish to secure by Letters Patent of the United States, is—

1. A field-magnet for dynamo-electric machines, cast in a single piece and broken into two or more parts by means of wedges driven 130 into holes where the divisions are desired for the purpose of facilitating the winding of the coils of wire thereon.
2. The field-magnet A, having the hole a

therein for facilitating the fracture or division of the magnet for the purpose of winding.

3. The field-magnet of a dynamo-electric machine, the pole-pieces broken apart and
5 united by sutures, as set forth.

4. The field-magnet of a dynamo-electric machine, the polar extensions united by a

ragged, broken, or irregular joint for forming a more perfect magnetic joint, as set forth.

WILLIAM L. SILVEY.
